 tion of Delaware

Application July 13, 1936, Serial No. 90,327

6 Claims. (Cl. 206—46)

This invention relates to an advantageous package of material containing a volatile constituent, and pertains particularly to a package which is sufficiently hermetic as to preserve the contained material at its desired content of volatile constituents, for a sufficiently long period to insure that there will be no appreciable loss during storage, so that the material will reach the ultimate user from the distributor in good condition.

One of the important objects of the invention is to provide a package which may be easily and inexpensively prepared and which will preserve a moisture-containing hydrocolloid composition or the like against loss of volatiles during storage periods.

The package of the present invention is primarily adapted for enclosing thermoplastic dental molding compositions. These compositions are semi-rigid when cool and must be heated to render the same fluent for use. Hydrocolloid compositions of this general type are described in U. S. Patent No. 1,672,776 and in the two U. S. patents of Harrison, Nos. 2,021,258 and 2,020,311. These materials have been conventionally marketed in the form of sticks or cylinders about one inch in diameter and four inches long, wrapped in tin-foil envelopes or the like, or as described in U. S. Patent No. 1,977,580, enclosed in a cellulosic envelope which is in turn enclosed in a moisture-impermeable envelope such as a glass bottle or a wax coating. Foil wrappers are objectionable in that they are not sufficiently moisture-retentive, and such wrappers also cause discoloration of the contained composition due to the metallic contact.

This discoloration prejudiced the user. In view of the fact that the package described in Patent No. 1,977,580 relies upon an external coating to provide the necessary moisture-impermeability to the package, and the internal coating is relied upon only as a container for the material during the boiling operation which is employed to render the material fluent, a package which has the external coating removed ready for use will be rendered worthless in the event that it is not used at that time, inasmuch as it cannot be again stored without undue moisture loss, except in the case of the glass bottle type of external container, which is relatively expensive to manufacture.

A particular object of the present invention is to provide a package which comprises a stick of thermoplastic material, containing volatile constituents, an impermeable envelope enclosing one end and substantially the full length of the stick and having an open end, and a solid closure member disposed at the open end of the envelope, in which

the envelope is in close compressive engagement with said closure member.

A further object of the invention is to provide a package which comprises a stick of thermoplastic material containing volatile constituents, an impermeable envelope enclosing one end and substantially the full length of the stick and which projects beyond the other end of said stick, and a solid closure member disposed within the projecting portion of said envelope, in which the closure member is provided with shoulder means, and in which the envelope is in close compressive engagement with said closure member at the position of said shoulder means.

A further object of the present invention is to provide a package comprising an impermeable envelope or container having a solid closure member at one end thereof, together with means providing positive compressive engagement of said envelope with said closure means.

A further important object is to provide a package of the character described, which comprises a moisture-impermeable envelope structure capable of elastic deformation at temperatures adjacent or in the neighborhood of the boiling point of water.

According to the present invention a moisture-impermeable envelope coating is provided for a body of such impression composition which adequately protects the same from contamination and preserves the moisture content thereof, such envelope coating being of a material which is of high mechanical strength at ordinary temperatures but readily capable of elastic deformation at elevated temperatures whereby the packages may be immersed in water and heated to render the contained composition fluent after which the package may be kneaded to homogenize the composition and render the same suitable for use, without danger of rupture of the envelope during the kneading operation.

The coating material should be one which, even at the elevated temperatures at which the contained impression composition is handled to render the same fluent, retains a high degree of mechanical strength, and preferably also remains substantially moisture-impermeable. The coating material is preferably one having a melting point somewhat in excess of 100° C. and relatively resilient and capable of elastic deformation at temperatures in the neighborhood of 100° C. The ability of the material to elastically deform at the high temperatures should persist to an important degree during cooling from adjacent 100° C. to in the neighborhood of 35° to 40° C., as it is com-

mon practice in dental technique to continue the kneading of the heated composition until the temperature thereof has dropped to a point such that it may be inserted within the mouth of a patient 5 without undue discomfort. The coating material is preferably also one which will exhibit a marked shrinkage upon cooling or drying, or one which may be shrunken in a convenient manner.

The envelope may be pre-formed of a material 10 such as a suitably moisture-proofed cellulosic composition (such as a material formed from an inter-solution of a cellulosic compound and a moisture-proofing material such as rubber, resins, resinous gums, and high melting-point waxes) or 15 from a resinous material such as the commercially available "Koroseal" (a polymerized vinyl halide). Alternatively, the envelope may be formed in position about the stick of hydrocolloid and the closure member, in which case I prefer to employ a 20 suitable solution of such a resin or other moisture-impervious composition, such as the commercially available material known as "Korolac" which comprises a solution of the above-mentioned vinyl resin in a suitable solvent. Of the 25 above-set-forth materials, the resin "Koroseal" (and the coating material resulting from the use of "Korolac") is particularly advantageous in view of its property of shrinking upon immersion in hot water. The coating formed from "Korolac" 30 exhibits this feature of shrinking in hot water to a greater degree than the envelope formed directly from the "Koroseal" material and for this reason greater latitude is had in the formation of the packages of the present invention when the envelope 35 coating is formed from "Korolac" solution.

The package of the present invention may comprise, essentially, an elongated stick or cylinder of thermoplastic material disposed within an envelope which extends substantially the full length 40 thereof and closed at one end, the other end of the package being closed by means of a solid and preferably substantially rigid closure member which is in tight compressional engagement with in said envelope. According to the preferred embodiment of the invention, a suitable compression member is provided exteriorly of said envelope in position to engage the aforesaid envelope and force the same into positive compressive engagement with said closure member, whereby said 45 closure member is maintained in position with respect to said envelope during the above-mentioned boiling and kneading operations.

Other features and advantages of the present invention will be brought out in the following 50 specific description of certain embodiments thereof, or will be apparent therefrom. The accompanying drawing illustrates such embodiments of the invention and referring thereto:

Fig. 1 is a broken away longitudinal view of a 55 package according to the present invention, in an intermediate step in the process of forming the same;

Fig. 2 is a longitudinal section of one end of the package shown in Fig. 1, at a later stage in 60 the process of manufacture;

Fig. 3 is a view corresponding to Fig. 2, showing the finished package;

Fig. 4 is a perspective view of a package formed 65 according to the steps shown in Figs. 1 through 3;

Fig. 5 is a sectional view corresponding to the upper end of the showing in Fig. 1, illustrating a further modification of the invention;

Fig. 6 is a view corresponding to Fig. 5 showing 70 a still further modified form of the invention;

Fig. 7 is a view corresponding to Fig. 5, showing a further modification of the package;

Fig. 8 is a view corresponding to Fig. 2, showing 75 the form of package illustrated in Fig. 7 in a further step in the process of completion;

Fig. 9 is a view corresponding to Fig. 3 showing the form of invention shown in Fig. 7 in completed condition;

Fig. 10 is a view corresponding to Fig. 1 showing 10 one end of a package in partly completed condition, in a further modification of the invention;

Fig. 11 is a view of one end of a finished package, with the envelope broken away, showing a further modification of the invention; and

Figs. 12 and 13 are views corresponding to Fig. 15 11, showing further modifications of the invention.

Referring to the drawing, and in particular to Figs. 1, 2 and 3, a stick of thermoplastic composition is shown at 1. A solid closure member 2, 20 formed of any suitable relatively rigid material upon which the contained composition will have no chemical or physical action, such as a medium hard vulcanized rubber, or one of the numerous synthetic resins or other molded plastic materials, 25 such as "Bakelite", is provided at one end of the stick 1 and is secured thereto in such manner as to support the weight of said stick when lifted by the closure member. This support may be provided by employing a closure member having 30 a recess 3 of sufficient size to receive one end of the stick 1, and a plurality of prongs or the like 4 are preferably provided adjacent the outer end of this recess in position to enter the body of material. The stick 1 may be mounted on the member 2 by forcing the said member over the end of the stick, making the prongs 4 pass through the material, and then twisting said member to provide a fresh surface against which said prongs may bear. The form of invention shown in Figs. 40 1 to 3 is preferably produced by a dipping operation, as by immersing the stick and the attached closure member in a fluid body or bath of coating material, and for this purpose I provide a suitable dipping member 5 which is preferably 45 provided with a conical lower end 6 adapted to fit within a coactively shaped hole 7 in the member 2. In the envelope-forming operation, the stick 1 and its thereto-secured closure member 2 may be supported vertically through the agency 50 of the member 5 and dipped into a suitable fluid bath of coating material such as the above-mentioned solution of "Koroseal", namely, "Korolac", or the like, preferably to a level somewhat above the upper end of said member 2, so that a portion 55 of the lower end of said member 5 is coated, as shown at 8 in Fig. 1, a substantially continuous envelope coating being provided for said stick, which envelope projects beyond the end of the said stick to cover the major portion of the closure member 2 as shown at 9. After the coating 60 9 has dried or solidified to a sufficient extent, the member 5 may be removed from the member 2 and the portion 8 of the envelope 9 is preferably forced down into the opening 7 as shown in Fig. 2. 65 The member 2 is preferably provided with shoulder means such as a projecting peripheral rim portion 11 at the upper end thereof, over which the envelope 9 extends. To complete the closure of the package, I may then place a small compression member 12 in position over the opening 7, as shown in Fig. 3, after which a deformable metal covering member 13 may be spun or crimped into place over the projecting rim portion 11 as shown at 14 in said Fig. 3. According 70 75

to this embodiment, the envelope 9 is forced into secure compressive engagement with the rim portion 1a of the opening 1 in the closure member 2, through the agency of the member 12, and is further secured in compressive engagement between the projection 11 and the portion 14 of the covering member.

In this form of the invention two separate sets of interengaging compression means are provided to force the envelope into compressive engagement with the solid closure member, namely, the member 12 which is in engagement with the envelope portion at the portion 1a of the closure member 2, and the portion 14 of the cover 13 which is in engagement with the envelope portion at the position of the rim 11. In each of the forms of the invention herein disclosed, the solid closure member is provided with shoulder means, and a compression member cooperating with the closure member in position to engage such shoulder means upon axial movement thereof with respect to the solid closure member in either direction, with a portion of the moisture-impervious envelope secured in positive compressive engagement between such shoulder means and the compression member.

If desired, in the above form of the invention the covering member 13 may be provided with a partially cut-away portion 15 of less width than the compression member 12, which may be pulled away from the main body of said covering member to enable the same to be removed by tearing the metal adjacent the end of the cut-away portion, as at 16 in Fig. 4, after the manner of the deformable seal customarily employed for catsup bottles and the like.

The material contained in the package is made ready for use by the dental technician by immersing the entire package in a body of water, which is brought to a boil and maintained at that temperature for a period of five to eight minutes. The package is then removed from the boiling water and kneaded to a smooth consistency and allowed to cool to a temperature in the neighborhood of 40° C. One end of the package is then opened as by means of a sharp knife or pair of scissors if the lower end 17 of the package is to be opened, or by tearing away the deformable portion of the covering member 13 as above described, and removing the closure member 2, if the upper end of the package is to be opened. The soft plastic material is then squeezed into an impression tray or the like and used by the dental practitioner in the customary manner. In the event that a package of material has been brought to a soft or "sol" condition by the above boiling operation and it was then decided that the material was not to be used, the unopened package may be allowed to cool and placed back in storage without damage by the boiling operation, the package not having been subjected to any permanent physical change and therefore still possessing its hermetic properties.

In Fig. 5 I have illustrated one end of a stick at 21 such as a stick of hydrocolloid or other thermoplastic composition, secured to a cap or closure member 22 through the agency of a spiral attachment member 23 embedded in said member 22. The closure member is attached to the stick 21 by rotating the same with respect to said stick to cause the spiral member 23 to enter the stick after the manner of a corkscrew. The closure member 22 is shown as provided with a peripheral groove 24 which may extend in spiral fashion about the circumference thereof, prefer-

ably for somewhat more than a complete revolution. After the member 22 and stick 21 have been dipped into the coating material through the agency of the member 5 as above described in connection with the first form of the invention, to form a coating 25, a suitable compression member such as a coil spring 26 is then preferably wrapped around the member 22 in position to engage the coating 25 and force the same downwardly into the groove 24 after the manner shown. The member 5 may be withdrawn either before or after this last operation, and the portion of the coating material which surrounds the opening from which the member 5 is withdrawn may be cut away, for example, at a position such as is indicated by the arrows a.

The form of package illustrated in Fig. 6 may comprise a stick of thermoplastic 26, an abutting solid closure member 27 provided with rather coarsely threaded side walls 27a and an enclosing envelope 28 which preferably extends over the end of the member 27 as at 28a. The member 27 may be secured to the stick 26 through the agency of a spiral attaching member 23 in accordance with the showing in Fig. 5, if desired, and the envelope 28 may be formed by the above-described dipping procedure through the agency of a suitable dipping member 5. The envelope 28 may be maintained in positive compressive engagement with the closure member 27 through the agency of a metal cap or the like 29 which is threadedly disposed over the end of the closure member to engage the portion of the coating 28 which overlies the threaded side walls 27a of said cap member, and force said coating portion into engagement with said member.

The form of invention illustrated in Figs. 7, 8, and 9 may comprise a closure member 31 provided with a thereto-secured spiral or corkscrew member 32 adapted to engage a stick 33 of material after the manner described in connection with Fig. 5, and an opening 34 in the upper end adapted to receive the tapered end 6 of a dipping member 5. The lower or inner end of the hole 34 is preferably recessed as at 35, the function of which will be subsequently brought out. The member 31 is attached to the stick 33 as above described, and the assembly is dipped into a bath of coating material to form a layer or envelope 36, being dipped to such a depth as to extend the coating material up about the lower end of the member 5 after the manner shown at 37. After the coating 36 has solidified or dried to the proper extent, the member 5 is removed and the portion 37 of the coating 36 is forced downwardly with in the opening 34 after the manner shown in Fig. 8. A resiliently deformable compression member such as a cork or stopper 38 is then forced into the opening 34 as shown in Fig. 9, forcing the portion 37 of the coating 36 outwardly into compressive engagement with the side walls of the opening 34. The member 38 is pushed into the opening 34 a sufficient distance so that the lower end thereof will enter the recessed space 35, where it will expand beneath the shoulders 39 of said recess and firmly position itself within the closure member 31, to position said closure member with respect to the envelope.

In Fig. 10 I have illustrated a modified form of dipping member 40, the upper end or handle portion of which is shown broken away and the lower end 41 of which is preferably enlarged and may be of substantially the same proportions as one or the other of the closure members 22 or 31 above described. The dipping member is pro-

vided with an axial bore 42 threaded to receive a corkscrew member 43, which member 43 extends the full length of the member 40 and terminates in a ring or the like 44 adapted to be grasped 5 between the thumb and forefinger to turn the corkscrew member and move it longitudinally of the member 40. According to this form of device, the portion 41 of the dipping member is brought into abutment with an end of a stick 45 of impression material such as a hydrocolloid or other thermoplastic, the portion 44 turned to force the lower end 46 of the member 43 into the stick 45, and the assembly is then dipped in the coating material to some such level as indicated at 10 15 47 to form a coating 48. After the coating 48 is properly solidified or dried, the portion 44 is rotated in the reverse direction, withdrawing the portion 46 from the stick 45, and the dipping member may then be forcibly removed from the 20 25 stick. Where a material such as "Korolac" is employed in the formation of the coating, the dipping member is more readily removed before the "Korolac" has thoroughly dried, as the material is somewhat more resilient in an undried condition. After the dipping member is withdrawn 30 35 from the envelope 48, a solid closure member 49 is inserted in its place, the upper end of the coating 48 being preferably cut away as shown at 51 in Fig. 11. The closure member 49 is shown 40 45 as provided with a peripheral recess 52 and after the member 49 is brought into position closely abutting the stick 45, a compression member such as a split spring ring 53 may be placed about the envelope in position to force the envelope 50 55 inwardly into said groove 52 into compressive engagement with the closure member 49, after the manner shown in Fig. 11. It will be apparent that the means shown in Figs. 5 and 11 for obtaining compressive engagement of the envelope 55 60 coating with the rigid closure member may be used interchangeably. It may be noted that the split spring ring 53 is not required to closely abut at its end portions particularly if the envelope material is formed of "Korolac" or a like material, in view of the pronounced shrinkage of that 65 70 material, which will cause the envelope to shrink close around the closure member into close engagement with the recess 52 in sufficiently tight compressive engagement therewith to prevent loss of volatiles from the package. Any space 75 which may occur between the ends of the ring will permit the envelope to stretch under the force of kneading when the material is brought to sol condition, and if the package is held in an upright position, with the closure member at the top, air contained in the package may be forced out through such space, due to the stretching of the envelope at that point, although the plastic hydrocolloid material will not escape through such a small space.

The package may be rendered adequately hermetic without utilizing the split ring 53, if desired, by immersing the closure end of the package in hot water to a level beyond the position 80 85 of the recess 52, to cause the envelope to shrink downwardly into the recess into secure engagement therewith.

The form of package illustrated in Fig. 12 may comprise a stick 61 provided with an envelope coating 62 which may be formed after the manner described in connection with Figs. 10 and 11, if desired, and a rigid closure member 63 placed at the end of the stick 61. The ends of the envelope 62 are brought over the edge of the member 63 as shown at 64, which member is

preferably of somewhat larger diameter than the stick 61 and is preferably also provided with a rounded rim 66 after the manner shown. The compression member preferably comprises a lid of metal or the like 65 which may be crimped or spun over the rim portion 66 of the member 63, forcing the portion 64 of the envelope 62 into firm compressive engagement with said member.

The form of package shown in Fig. 13 may comprise a solid closure member 71 attached to a hydrocolloid stick 72 in any suitable manner as through the agency of a corkscrew member 73 corresponding to the member 23 shown in Fig. 5, and said closure member 71 is preferably provided with a peripheral recess 74 in a manner 15 comparable to that shown at 52 in Fig. 11. Before the envelope 76 is formed on the package, I dispose a suitable positioning means such as a split ring 75 within the recess 74. This positioning means is not required to tightly engage this 20 recess, but should be of such proportion as to maintain its position with respect thereto. The envelope 76 is then formed by dipping the package into a suitable solution such as the above-mentioned "Korolac", and the envelope material 25 will flow inwardly about the member 75 and also coat the outside thereof so that said member 75 becomes embedded in the envelope coating as shown at 77. The subsequent drying of the envelope material will cause the envelope to tightly 30 engage the closure member 71 whereby moisture loss from the package is prevented and in any subsequent boiling and/or kneading operation, the member 75 serves to position the closure member 71 with respect to the envelope so that 35 endwise dislocation thereof under pressure will be prevented.

In each of the above-described forms of the invention, a suitable compression member is provided to positively force the envelope into compressive engagement with the solid closure means. When the coating is formed from "Korolac" or similar material, there will be sufficient compressive engagement of the envelope with the solid closure member upon drying, even in the absence of the compression or positioning member above described, that escape of moisture from the contained material is substantially prevented. For example, specimens have been subjected to an extended storage period without significant 50 loss in moisture content, in the absence of any compression or positioning means. The compressive engagement of the envelope with the closure means is also in general adequate to maintain the closure member in position during the above-mentioned boiling operation, but in view of the fact that the envelope material will soften to such an extent in boiling water that the principal proportion of the compressive engagement is lost, the heated package will not stand any degree of handling such as is produced during a kneading manipulation of the package, and for this reason I prefer to employ the above-mentioned compression or positioning member to maintain the desired engagement of the envelope with the closure member during the boiling and kneading operation. In view of the fact, however, that these impression compounds are frequently brought into the desired fluent or "sol" state in a special form of apparatus, such as a mixing syringe, I contemplate the possibility of forming the complete package in the absence of this compression or positioning member, inasmuch as the package in this form is adequate to prevent significant loss of moisture 75

from the contained hydrocolloid, and is thus a commercially operative package.

Each of the above-described forms of package may alternatively be prepared by the use of a pre-formed capsule or the like instead of the above-set-forth dipping procedure. The forms shown in Figs. 1 to 4 may thus be prepared by employing a capsule of somewhat greater length than the stick 1 plus the closure member 2, folding the projecting end over the head of the member 2, immersing that end of the package into boiling water for a few seconds, and then applying the compression member 12 and the covering 13 as above described. The forms shown in Figs. 5, 6, 10, and 11 may be comparably prepared, and particularly, in the case of the forms shown in Fig. 6, the "Korolac" material will shrink about the threaded portion 27a into very secure engagement with the closure member 27. When a preformed capsule is employed in the formation of the type of package shown in Figs. 7, 8, and 9, I preferably use a capsule of sufficient length that the projecting end thereof may be tucked downwardly into the opening 34, the envelope then being thoroughly heated by immersion in hot water at that end of the device to soften the envelope, and the stopper member 38 forced into the opening 34 when the material is still in heated condition.

In the formation of the envelope coating by a dipping procedure, I may employ a mixture of cellulose and rubber in a suitable solvent, such as may be formed from an intermixture of two equal volumes of cyclohexanol or cyclohexanol acetate in which from 10% to 30% by weight of celluloid and raw rubber has been respectively dissolved, the mixture being preferably evaporated to a thin honey-like consistency.

Where the celluloid-rubber mixture is employed, it will be necessary to allow the envelope coating to dry to some extent before the compression member is placed in engagement therewith. In general, I prefer to employ a composition which will solidify or gel at a more rapid rate than the above-mentioned celluloid-rubber mixture, such as the above-mentioned "Korolac". In the above-mentioned "Korolac" the "Koroseal" is in solution at a relatively high temperature, but solidifies to a gel form at a relatively lower temperature. When the stick of hydrocolloid material and the associated closure member is dipped into a heated bath of "Korolac", the material will gel out on contact with the hydrocolloid composition and form a continuous envelope over the dipped area, which may be handled almost immediately.

As a specific example of the formation of envelope coatings by a dipping procedure where the envelope coating is formed of the resin "Korolac", I heat a body of "Korolac" containing approximately 10% "Koroseal" to a temperature in the neighborhood of 130° C. The coating thus formed will be in the neighborhood of one-eighth of an inch thick on gelling, which coating will dry down to a layer approximately five-thousandths of an inch thick in a period of 48 hours, during which the above-described shrinkage takes place. Where heavier coatings are desired, multiple dipping may be practiced in such manner as to form a plurality of superimposed thicknesses of coating material in the production of membranes in excess of 0.01 inch in thickness. Alternatively, the thickness of the coating can be varied by a control of the temperature of the dipping bath and the tempera-

ture of the stick of hydrocolloid when dipped. For example, if a temperature lower than 130° C. is employed for the dipping bath, a thicker coat will be formed and similarly, if the stick of hydrocolloid is chilled before dipping, a heavier coat will result.

Other methods of attaching the rigid closure member to the stick or cylinder of hydrocolloid material will occur to those skilled in the art and I do not choose to be limited to the specific arrangements herein delineated, but rather to the scope of the appended claims. Furthermore, the dipping member 5 may be left in engagement with the finished package, if desired, either by permanently attaching the same to the rigid closure member or by forming the same integrally therewith, so that a handle member will be provided for use by the dental practitioner or his technician in the boiling operation, as will be apparent to one skilled in the art.

I claim:

1. A package of reversible moisture-containing thermoplastic impression material which is semi-rigid when cool and requires heating to render the same fluent for use, comprising: a stick of such impression material; a flexible moisture-impervious envelope enclosing one end and substantially the full length of said stick and projecting beyond the other end thereof; a solid closure member disposed within the projecting portion of said envelope and provided with shoulder means; compression means cooperating with said closure means in position to engage said shoulder means upon axial movement with respect thereto, and said envelope having a portion secured in positive compressive engagement between said compression means and said shoulder means.

2. A package as set forth in claim 1, said envelope being formed of a material having high mechanical strength at temperatures between atmospheric temperature and 100° C. and capable of resilient deformation at temperatures between 35° and 100° C.

3. The package set forth in claim 1, said shoulder means on said closure means comprising a peripheral recess, and said compression means having a portion extending within said recess.

4. The package set forth in claim 1, said shoulder means comprising an inwardly directed recess in the outer end of said closure means, and said compression means comprising a plug member disposed within said recess.

5. A package of reversible moisture-containing thermoplastic impression material which is semi-rigid when cool and requires heating to render the same fluent for use, comprising: a stick of such impression material; a flexible moisture-impervious envelope enclosing one end and substantially the full length of said stick and projecting beyond the other end thereof; a solid closure member disposed within the projecting portion of said envelope and provided with coarsely threaded side walls; a threaded cap member engaging said envelope at said projecting portion and forcing the same into compressive engagement with the coarsely threaded side walls of said closure member.

6. A package of reversible moisture-containing thermoplastic impression material which is semi-rigid when cool and requires heating to render the same fluent for use, comprising: a stick of hydrocolloid material; a flexible moisture-impervious envelope enclosing one end and

substantially the full length of said stick and projecting beyond the other end thereof; a solid closure member disposed within the projecting portion of said envelope and provided with a projecting peripheral rim portion at the outer end thereof, and a compression member engag-

ing said envelope at said projecting portion and forcing the same into compressive engagement with said closure member at the position of said rim portion.

HENRY F. BOEGER. 5

CERTIFICATE OF CORRECTION.

Patent No. 2,135,790.

November 8, 1938.

HENRY F. BOEGER.

It is hereby certified that the State of Incorporation of the assignee in the above numbered patent was erroneously given as "Delaware", whereas said State should have been given as --California--, as shown by the record of assignments in this office; and that the said Letters Patent should be read with this correction therein that the same may conform to the record of the case in the Patent Office.

Signed and sealed this 18th day of March, A. D. 1941.

(Seal)

Henry Van Arsdale,
Acting Commissioner of Patents.
